J. F. CARPMILL

AUTOMOBILE HOOD FASTENER

Filed Oct. 5, 1922

FIG. I.

FIG. 2.

FIG. 3.

FIG. 4.

FIG. 5.

INVENTOR

J. J. Corson

Walt L. Johnson
ATTORNEY

UNITED STATES PATENT OFFICE.

JOHN F. CARPMILL, OF NEW BRITAIN, CONNECTICUT.

AUTOMOBILE HOOD FASTENER.

Application filed October 5, 1922. Serial No. 592,555.

To all whom it may concern:

Be it known that I, JOHN F. CARPMILL, a citizen of the United States, residing at New Britain, in the county of Hartford and State of Connecticut, have invented certain new and useful Improvements in Automobile Hood Fasteners, of which the following is a specification.

This invention relates to an automobile-hood fastener, and among the objects of the invention are the provision of a device of this nature which is thoroughly efficient in pulling down the hood over the engine, in a thoroughly tight manner and at the same time applying a lateral pressure against the side of the hood thus to eliminate as far as practicable the common rattle which is usually present in hoods of the ordinary kind. The article herein set forth is of the same general nature and has practically the same motives as that covered in my application Ser. No. 592,556 filed October 5, 1922.

In the drawing accompanying and forming part of the present specification, I have shown in detail one of the several forms of embodiment of the invention; which to enable those skilled in the art to practice the invention will be set forth fully in the following description.

Clearly I am not restricted to this disclosure. I may depart therefrom in a number of particulars within the scope of the invention defined by the claims following said description.

Referring to said drawing:

Fig. 1 is a sectional elevation as seen for instance from the rear, of a hold-down device involving the invention.

Fig. 2 is an elevation as seen from the right in Fig. 1.

Fig. 3 is a section on the line 3—3 of Fig. 2.

Fig. 4 is a view corresponding somewhat with Fig. 2 of a modified structure.

Fig. 5 is an elevation as seen from the right in said Fig. 4.

Like characters refer to like parts throughout the several views.

In the drawing I have shown a part of the front portion of the chassis 2 of an automobile. The chassis or frame at its forward portion supports an engine or motor which I have not illustrated because in itself it constitutes no part of the present invention. The engine is covered by a

hood 3, the sides 4 of which, generally practically duplicates of each other, are pivoted to the body or top portion of the hood to permit either side 4 to be swung up when necessary, to obtain access to the engine or motor. When closed the sides fit against the chassis 2 and owing to the motion of the engine in the car are caused to vibrate, the vibration causing objectionable noises, and it is my purpose to remove as far as possible, such noises.

The sides 4 are held down by one or more hold-down members such as those denoted in a general way by 5. Usually there are two of these holding down members connected with each side 4.

The hold-down member 5 shown involves a tubular body or sleeve 6 which incloses a rod 7 having what is represented at its upper end as the head 8 which closely fits and slides in the tube or sleeve 6. The rod 7 as illustrated, is surrounded by the coiled spring 9, the upper end of which bears against the head 8 while the lower end bears against the bottom of the tubular body 6 from the lower end of which the rod 7 extends. The spring tends constantly to longitudinally separate the two main elements of the hold-down member.

As shown the lower end of the lower end portion of the rod 7 extends through a central opening 10 in the top of the semi-spherical base piece 11 which is marginally united to the chassis 2 or to a facing strip 11' thereon. The piston rod 7' has as shown the foot 12 which prevents the rod 7 from being pulled from the semi-spherical body or cap 11, although the rod is free to swivel and to move laterally and universally after the fashion of a balljoint. The upper end of the tubular body is closed with a head or cap 13 which can be fitted thereto in some rigid manner and which may have on its upper side the thumb portion 14 to facilitate its movement when necessary. In addition to this, the head may have the lateral finger pieces 15 by which the sleeve or tube 6 when required can be lifted. Beside the pulling down effect of the holding down members 5, the same is intended to exert a lateral pressure on the hood, and the means shown for this purpose will now be set forth.

The side 4 may as shown have attached thereto the bracket member 17 which may be held in place by screws or rivets as 17'.

To the outer end of the arm or lug of the bracket 17 is jointed as by pivoting, a catch member as 18 which hangs down from the arm of the bracket and which may have 5 attached to the inner side thereof at the free end the rubber pad 19 which is intended to press against the hood side of the side 4 and which may for example be attached to the catch member 18 or the shank thereof as 10 by the rivet 19'. On the outer side of the catch member 18 and about midway of the height or length thereof, is the arm 20 having on the upper side thereof the recess 21 which is adapted to receive the hook 22, on 15 the inner side of the head or cap 13 of the holding down member 5. The parts being shown as engaged in the several views at which time as will be clear the hold-down member 5 applies a powerful pull to the side 20 4 and at the same time applies a practically equal lateral pressure to the side, acting thereupon through the catch member 18.

The foregoing description applies especially to the structure shown by Figs. 1 to 3 25 inclusive. In Figs. 4 and 5, I represent one of many modifications and in these two views the parts which correspond to those appearing in the other illustration will bear similar prime marks with reference characters. The hold-down member 5' is practically exactly like the hold-down member 5, so that the same need not be described in detail. The side 4' of the automobile hood is shown as supporting an angular bracket 30 17'', the upper arm of which extends through a hole 4'' in the hood side 4'. This bracket 17'' is furnished on its outer side with a projection 17a and has on its inner side and lower end the rubber pad or foot 35 19'' held in place by the rivet 19a, the pad or foot 19'' being adapted to bear against the hood side 4'. The inwardly extending arm of the bracket 17'' projects through the opening 4'' and also extends centrally 40 through the washer 23. This washer 23 fits 45 flatwise against the inner surface of the

hood side 4'. The bracket 17'' at its extreme inner end carries the pin 24 rigid therewith and which fits in the groove or channel 25 in the washer 23 as shown best 50 in Fig. 5. This construction provides a means for insuring the proper holding down pull and at the same time sufficient lateral pressure to prevent vibration of the sides of the hood. 55

What I claim is:

1. In an automobile hood fastener, the combination of a tube, a piston rod in the tube having a head in slidable engagement therewith and extending from the tube, a coiled 60 spring surrounding the piston rod and engaging said head and also engaging the lower end of the tube, a part to which the piston rod is pivoted, a cap closing the upper end of the hood, and provided with lateral branches, and a bracket having means by which it can be held in engagement with the hood of an automobile and a soft pad pivoted to the bracket and adapted to engage said hood. 70

2. In an automobile hood fastener, the combination of a tube, a piston rod in the tube having a head in slidable engagement therewith and extending from the tube, a coiled spring surrounding the piston rod 75 and engaging said head and also engaging the lower end of the tube, a part to which the piston rod is pivoted, a cap closing the upper end of the hood, and an angular bracket having means by which it can be attached to the hood of an automobile and a shank pivoted to the bracket and provided with a soft pad to engage said hood; said cap having an arm, and the shank having an arm to be engaged by the arm of the cap. 80 85

In testimony whereof I hereby affix my signature.

JOHN F. CARPMILL.
